HINGE

Elbert J. Walton, Denver, Colo., assignor to Harry
G. Liebhardt, Denver, Colo.

Application November 14, 1939, Serial No. 304,325

5 Claims. (Cl. 16—131)

This invention relates to improved hinge construction.

As is well known to those skilled in the art, automobile doors, for instance, require a rugged hinge, and due to the curvature of such doors, the axis of angular movement of the hinges upon which automobile doors are hung is usually set out from the car body. Furthermore, an automobile door should have a stop to limit its angular opening movement; otherwise, damage may result to the door or the car body.

There are numerous other places where rugged hinges having set out axes of angular movement and having stop means, are advantageous; for instance, on refrigerator doors.

The present invention is herein illustrated as embodied in a hinge especially adapted for use on automobile doors, but it is to be understood that hinges made according to this invention as defined in the appended claims, may be used for many different types of installation and the invention is not limited to automobile door hinges or any other specific installation.

A principal object of this invention is to provide a strong rugged hinge of novel construction that has its axis of angular movement set out from the hinged members to which it is attached.

Another object is the provision of a substantially dustproof and tamperproof hinge that readily can be lubricated.

Another object is to provide a hinge of this character that has means for limiting the angular movement of the hinged members.

A further object is to provide a hinge having a ball-and-socket type hinge joint in contradistinction from a hinge pin.

Still another object is to provide in a hinge of this character, means whereby the hinge readily may be assembled and disassembled and which will hold its assembled relationship without accidental loosening.

A still further object is to provide a hinge whose axis of angular movement may be selectively positioned within certain limits, according to installation requirements.

Other objects and advantages reside in details of design and construction which will be more fully disclosed in the following description and in the drawings wherein like parts have been similarly designated and in which:

Figure 1 is a front elevation of a hinge made according to this invention;

Figure 2 is a top plan view of the hinge shown in Figure 1, but drawn to a slightly smaller scale;

Figure 3 illustrates the normal open position of the hinge shown in Figure 2;

Figure 4 illustrates the extreme open position of the hinge shown in Figures 2 and 3;

Figure 5 is a fragmentary sectional view taken along the line 5—5 of Figure 1;

Figure 6 is a front elevation partially in section, of a hinge made according to a preferred embodiment of the invention; and

Figure 7 is a fragmentary cross sectional view taken approximately along the line 7—7 of Figure 6.

In order to record an operable reduction to practice of the present inventive concept, the hinge illustrated herewith will be described in detail. However, it is to be understood that, since changes may occur to those skilled in the art, this example is not intended to express or imply any limitation to the invention, the scope of which is, in reality, measured by the appended claims.

The present example of hinge construction embodies certain novel ornamental design features which are set forth and claimed in the 25 Design Patent No. D-118,715, issued January 30, 1940. Therefore, the mechanical features of the improved hinge will be described and claimed in this present application, apart from the novel appearance of the hinge. The form and positioning of the hinge illustrated in Figures 6 and 7 is preferred for installation upon automobile doors.

An angle plate 6 is adapted to be attached securely to the door frame or, in other words, 35 the stationary one of the hinged members. Another angle plate 7 is adapted to be attached to the movable one of the hinged members, i. e., the door. Each hinge plate 6 and 7 may be provided with a boss 8 to facilitate attachment to the hinged members, as by means of bolts or screws passing through said bosses.

A projection 9 terminating in a horizontal internally threaded cylinder 10 is carried on the 45 stationary angle plate 6. An arm 11 is carried on the movable angle plate 7 and terminates at its outer extremity in a ball 12 which is carried in the interior of the cylinder 10, a socket for said ball being built up of novel component parts within the cylinder 10.

The socket for the ball 12, as best illustrated in Figure 5, is provided in the cylinder 10 by means of case hardened companion threaded-plugs 13 and 14, each of which has an arcuate depression that fits the outer contour of the ball. 55 The threaded-plugs 13 and 14 may be provided

with a screwdriver slot, not shown, and they are externally threaded so that they may be screwed into the cylinder 10 from opposite directions to positions immediately adjacent sides of the ball 12, thus forming a socket. Obviously, the ball 12 is rotatable in this socket between the companion threaded-plugs 13 and 14 and it is manifest that the axis of rotation of the ball 12 may optionally be positioned within the limits of the cylinder 10 as desired.

After the companion threaded-plugs 13 and 14 have been suitably positioned, retaining springs 15 may be next inserted into the cylinder 10 to bear upon the threaded-plugs 13 and 14 respectively, after which a retaining threaded-plug 16 may be screwed into the cylinder 10 to compress the spring 15 that is adjacent to and bearing upon companion socketed threaded-plug 14, and a retaining threaded-plug 17 is screwed into the opposite end of the cylinder 10 to compress the other retaining spring 15 that bears upon companion socketed threaded-plug 13. Thus, the entire socket assembly is held in its selected position against accidental loosening, but the entire socket assembly readily may be disassembled if and when desired, by removing the threaded-plugs 16 and 17, the springs 15 and the companion socketed threaded-plugs 13 and 14.

As illustrated in Figure 4, the extreme open position of the hinge or, in other words, the extreme angular movement of the movable angle plate 7 with reference to the stationary angle plate 6, is the position where the angle plate 7 contacts the outer portion of the retaining threaded-plug 17 which is extended for this purpose.

The threaded-plug 16 may be provided with a common screwdriver slot as shown at 16a, Figure 1, and due to the particular "streamlined" shape of the other retaining threaded-plug 17, it is preferred to provide a number of relatively small holes 17a into which a suitable tool may be inserted for turning this threaded-plug.

Thus, is provided a strong rugged hinge that is suitable for hanging an automobile door or other hinged member, particularly any type of heavy door. The hinge is provided with a ball-and-socket joint instead of the common hinge pin and the axis of angular movement of the hinge is set out from the hinged members and may be selectively positioned within certain limits, as desired. The novel built up socket for the ball may readily be assembled and disassembled and it remains securely locked in its assembled position.

The extended portion of the retaining threaded-plug 17 serves the useful purpose of providing stop means for the angular movement of the angle plate 7 and the door attached thereto, with reference to the stationary angle plate 6. A door mounted on angle plate 7 cannot possibly contact the stationary structure to which the stationary angle plate 6 is attached. A door mounted upon such a hinge swings entirely clear from the stationary structure when it is opened and remains entirely clear until again closed.

Obviously, the horizontal distance that the axis of angular movement is set out from the stationary structure may be varied in the original construction of the hinge by varying the distance of the center of the cylinder 10 from the stationary angle plate 6. The exact fitting of the latch edge of the door with reference to the door frame is under selective control by the optional posi-

tioning of the companion socketed threaded-plugs 13 and 14 in the threaded cylinder 10.

Referring particularly to the form of hinge illustrated in Figures 6 and 7, which is the preferred form and positioning for use on automobile doors, the hinge is preferably mounted so that the arm 11 terminating in the ball 12, hangs in the socket provided by case hardened companion threaded-plugs 13 and 14 in cylinder 10, and projects downwardly therefrom.

The inner mechanical details of construction in the form of the hinge illustrated in Figures 6 and 7 is entirely comparable to that well illustrated in section in Figure 5, but it has not been considered necessary to repeat these details in Figure 6.

A typical grease gun connection 20 is mounted upon the top of the cylinder 10 and is in ordinary communication with the interior of the cylinder 10, thus providing means for thoroughly lubricating the ball and socket joint. Since the opening in the bottom of cylinder 10 through which the ball 12 is inserted into its socket, opens downwardly, practically no dust will enter the ball and socket joint. This is highly advantageous in automobile construction.

A hinge made according to any of these examples is virtually tamper-proof since there is no hinge pin that can be forced out of the hinge as in ordinary hinge construction. A door mounted upon a hinge made according to this invention and locked in closed position cannot be opened or removed by tampering with the hinges.

The hinges herein illustrated are especially attractive in appearance and as above pointed out, their ornamental design features are being set forth and claimed in another application.

To avoid any tendency to turning the threaded companion socket-forming plugs 13 and 14 by the hinge ball 12 socketed therebetween, said threaded plugs 13 and 14 may conveniently be made to fit tightly in the threaded cylinder 10.

What I claim and desire to secure by Letters Patent is:

1. A hinge comprising a normally stationary plate, an internally threaded cylinder carried on the plate and spaced away from said plate, companion socketed threaded-plugs in the cylinder forming a socket, means comprising compression springs positioned to bear against said socket-forming threaded-plugs and retaining threaded-plugs pressing said springs for holding the socketed threaded plugs in selected positions in said cylinder, a relatively movable plate, and an arm on the movable plate having a ball terminal held in the socket.

2. A hinge comprising a normally stationary plate, an internally threaded cylinder carried on the plate and spaced away from said plate, companion socketed threaded-plugs in the cylinder forming a socket, means comprising compression springs and retaining threaded-plugs for holding the socketed plugs in selected positions in said cylinder, a relatively movable plate, and an arm on the movable plate having a ball terminal held in the socket, one of said retaining plugs projecting from said cylinder in a position to limit relative angular movement of the movable plate in one direction.

3. A hinge comprising a stationary plate, an internally threaded normally horizontal cylinder carried on the plate and spaced away from said plate, companion socketed threaded-plugs in the cylinder forming a socket, means for retaining the threaded-plugs in selected positions in

said cylinder, a relatively movable plate, and an arm on the movable plate having a ball terminal held in the socket, there being an opening in a side of the cylinder to admit said ball.

4. A hinge comprising a stationary plate, a normally horizontal internally threaded cylinder carried on the plate and spaced away therefrom, companion socketed threaded-plugs threaded into the cylinder providing a socket, compression springs bearing against the respective socketed threaded-plugs, spring-pressing retaining threaded-plugs screwed into the cylinder at opposite ends thereof, a relatively movable plate, an arm on the movable plate terminating in a ball carried in said socket, there being an opening in a side of said cylinder to admit said ball, one of said retaining threaded plugs projecting from the cyl-

inder in a position to limit relative angular movement of the movable plate in one direction.

5. In a hinge for an automobile door or the like inclusive of a relatively stationary element and an angularly movable element, the improvement which comprises a normally horizontal internally threaded cylinder having a downward side opening and mounted on the stationary element and spaced therefrom, companion socketed 10 plugs threaded into said cylinder, resilient means for resisting movement of said plugs from their selected position with reference to the cylinder, and an arm on the movable element extending upwardly into the cylinder and having a ball terminal held between said plugs.
